UNITED STATES PATENT OFFICE.

NICOLAUS AUGUST OTTO, OF COLOGNE, ASSIGNOR TO THE GAS MOTOREN FABRIK DEUTZ, OF DEUTZ ON THE RHINE, GERMANY.

IGNITING APPARATUS FOR GAS OR OIL MOTOR ENGINES.

SPECIFICATION forming part of Letters Patent No. 390,092, dated September 25, 1888.

Application filed March 27, 1888. Serial No. 262,631. (No model.) Patented in England February 29, 1888, No. 3,095, and in Belgium March 14, 1888, No. 81,028.

To all whom it may concern:

Be it known that I, NICOLAUS AUGUST OTTO, a citizen of Prussia, residing at Cologne, in the German Empire, engineer, have invented certain new and useful Improvements in Igniting Apparatus for Gas or Oil Motor Engines, (for which I have obtained patent in Belgium, No. 81,028, dated March 14, 1888, and have made application for patent in Great Britain, No. 3,095, dated February 29, 1888,) of which the following is a specification.

This invention relates to my gas motor engines where the charges are ignited by means of an externally-heated tube, and in which the 15 passage leading back from the igniting-port of the engine-cylinder to the said igniting-tube had an extension beyond the latter, forming a chamber for the reception of a portion of the combustible charge which entered the said 20 passage and heated igniting-tube on opening the slide or valve establishing the communication between these parts and the cylinder-port.

The present invention relates to an improved arrangement of the said passage, igniting-tube, chamber, and slide or valve, so as to insure, first, that the combustion-gases that remain in these parts shall be effectually cleared out of the passage before the entrance 30 of the next charge of combustible gas, and, secondly, that the gases remaining in the said parts shall be reduced to atmospheric pressure before the entrance of the next combustible charge, so as to enable the latter to effectually 35 penetrate into the same and to effect its certain and rapid ignition. For this purpose the several parts are arranged as follows: The valve or slide which opens and closes the communication between the cylinder and the said 40 parts, instead of being situated immediately against the cylinder, between this and the passage leading to the heated firing-tube, is situated between the said passage and the firing-tube, and the before-mentioned chamber is 45 made to communicate with the passage at a point between the valve or slide and the cylinder, so that the chamber and passage are always in communication with the cylinder. Furthermore, the valve or slide is so actuated

by a cam or eccentric that the communication 50 between the cylinder and the passage, the chamber, and the heated igniting-tube is kept open during the working-stroke, the expelling-stroke, and in some cases, also, during the suction-stroke of the engine, while during the 55 compression-stroke the communication with the igniting-tube is closed, the passage and chamber still remaining open to the cylinder. The result of this arrangement is that during the expelling and suction strokes, the several 60 parts being open to the atmosphere, the residual combustion-gases from the last ignition will be free to escape until they are at atmospheric pressure, and that on the following compression-stroke the small volume of com- 65 bustion-gases remaining in the passage will be readily forced into the chamber by the compressed combustible charge entering from the cylinder, the passage becoming thus entirely 70 filled and the chamber partially so by such charge, so that on the valve or slide being now opened only combustible gas will enter the igniting-tube, thus insuring a certain and rapid ignition of the charge.

The arrangement of the igniting apparatus 75 for carrying out the above-described mode of action can be variously modified. Thus, according to one arrangement, the passage from the cylinder extends vertically upward to the heated igniting-tube, immediately below which 80 is arranged a sliding plug-valve at right angles to the passage for closing the communication, the stem of which valve is acted upon by a helical spring tending to keep the valve open, this being closed at the desired moment by a 85 lever acted upon by a cam on a counter-shaft of the engine. The chamber is in the form of a tube projecting horizontally from the passage at a point below the valve.

It is found advantageous to effect the ignition 90 of the charge somewhat sooner when the engine is running fast than when running slow, and in order to enable this to be done the cam acting on the valve is arranged so that it can be shifted on the shaft in order to bring a part 95 thereof which is more in advance to act upon the valve-stem when the engine is to run at a quick speed. The igniting-tube is surrounded

by the annular flame of a Bunsen burner inclosed in a cylindrical casing.

According to another modification the passage projects horizontally from the side or end 5 of the cylinder, and the igniting-tube projects vertically upward from the end thereof, the valve being situated vertically below the igniting-tube, and the tubular chamber extends vertically downward from an intermediate point 10 of the passage.

In the accompanying drawings, illustrating 15 my invention, Figure 1 is a transverse sectional view of the cylinder of a gas-motor engine, showing my invention applied thereto, the parts being in position to establish communication 20 between the cylinder and the igniting-tube; Fig. 2, a similar view showing communication closed between the cylinder and igniting-tube; Fig. 2^a, a detail view of the cam; Figs. 3 and 4, similar views showing modifications 25 of the invention.

Referring to the drawings, Figs. 1 and 2 show an arrangement in which the passage *h*, extending vertically up from the engine-cylinder, has the externally-heated igniting-tube *r* fixed to its upper end, the tube *r* being heated by the surrounding flame of a Bunsen burner, *a*, supplied with gas through a pipe. At an intermediate point of the passage *h* is the tubular chamber *r'*, extending at right angles therefrom, and at a point between the chamber *r'* and the igniting-tube is the sliding piston-valve *v*, the stem of which is acted upon by a helical spring, *f*, which tends to keep the valve 30 open, as shown.

A lever, *b* *c*, bears with its one arm upon the end of the valve-stem, and with its other end upon a cam, *n*, on the counter-shaft *e*, driven at half the speed of the engine-shaft. This 40 cam is so formed that during that part of the revolution of *e* which corresponds to the working, expelling, and suction strokes of the engine it does not act upon the valve, so that during this time the passage *h*, chamber *r'*, and 45 igniting-tube, being in communication with the cylinder, will only contain gases at atmospheric pressure; but as the piston is about to commence its compressing-stroke the cam *n* is made to close the valve *v* and to keep this 50 closed until the end of such stroke. During this time a portion of the compressed combustible charge enters the passage *h* from the cylinder, thereby forcing the small quantity of combustion-gases remaining in it from the last 55 ignition into the tube *r'*, which also becomes partly filled with the combustible charge, so that on the valve being now opened again by the spring only combustible gas will pass into the igniting-tube, and consequently the certain 60 and rapid ignition of the cylinder-charge will be insured. When the valve *v* is open, it is pressed by the spring *f*, with its coned face, upon a coned seating in the casing, thus preventing any escape of gas through the hole 65 for the valve-stem. The cam *n* may either be

fixed on the counter shaft *e*, so as always to effect the closing of the valve at a determined moment; or it may be on a sleeve, *m*, capable of being slid on the shaft *e*, and be made some width, with one side sloping, as shown at Fig. 70 2^a, so that by varying the position of the cam relatively to the lever *c* the moment at which the valve is made to open so as to effect the ignition may be varied. It is found that when a gas-motor engine is running at a quick speed 75 it is advantageous to effect the ignition of the charge somewhat sooner than when it is running at a slower speed, and this may be effected by the above-described arrangement by shifting the cam so that the part with shorter dwell 80 acts upon the lever *c*.

Figs. 3 and 4 show the modified arrangement of the several parts.

The passage *h* here extends horizontally from the side of the cylinder, with the igniting-tube *r* projecting vertically upward from its end, and the tubular chamber *r'* projecting vertically downward, the valve *v* being also moved vertically from below. The several parts are otherwise of the same construction 85 and action as described.

Having thus described the nature of my invention and the best means I know for carrying the same into practical effect, I claim—

1. In apparatus for igniting the charges of 90 gas-motor engines by means of an externally-heated igniting-tube, the combination of a passage leading from the cylinder to the firing-tube, a valve or slide arranged to close the communication between the tube and passage, and a chamber 100 communicating with the passage so that the passage and chamber are always in communication with the engine-cylinder, but the communication with the igniting-tube is closed by the valve during the compression-stroke of the 105 engine, substantially as and for the purposes herein described.

2. In igniting apparatus of gas-motor engines, the combination of a passage, *h*, leading to the cylinder, externally-heated igniting-tube *r*, tubular chamber *r'*, communicating with passage *h*, and valve *v*, for closing the communication between the igniting-tube and passage *h* during the compression-stroke of the 110 engine, substantially as herein described. 115

3. In combination with the valve *v*, for closing the communication between the igniting-tube *r* and the passage *h*, an adjustable cam, *n*, of variable width, so formed that when placed in one position for a quick speed of the engine 120 it will effect the opening of the valve earlier than when placed in another position.

In testimony whereof I have signed my name to this specification, in the presence of two subscribing witnesses, this 12th day of March, A. 125 D. 1888.

NICOLAUS AUGUST OTTO.
